(57) **CLAIM**

The ornamental design for border for a plate or bowl, as shown and described.

DESCRIPTION

FIG. 1 is a top plain view of a border for a plate or bowl showing my new design;

FIG. 2 is a side elevation view thereof;

FIG. 3 is a bottom plain view thereof; and,

FIG. 4 is a side elevation view thereof.

The broken lines in the drawings are for illustrative purposes only and form no part of the claimed designs.
